Nelson M. Howard*

UNITED STATES PATENT OFFICE.

JOSEPH GOULBOURN, OF LEICESTER, ENGLAND, ASSIGNOR TO UNITED SHOE MACHINERY CORPORATION, OF PATERSON, NEW JERSEY, A CORPORATION OF NEW JERSEY.

MACHINE FOR OPERATING UPON SHOES.

Application filed October 22, 1921. Serial No. 509,696.

To all whom it may concern:

Be it known that I, JOSEPH GOULBOURN, a subject of the King of England, residing at Leicester, Leicestershire, England, have 5 invented certain Improvements in Machines for Operating Upon Shoes, of which the following description, in connection with the accompanying drawings, is a specification, like reference characters on the drawings indicating like parts in the several figures.

This invention relates to machines for operating upon shoes, such, for instance, as heel-attaching machines, and more particularly to those of the type in which fastenings are driven to attach a heel to a shoe from the inside. It is especially concerned with the provision of heel-engaging members capable of effectively exerting pressure upon wooden or other Louis or like heels, which have a comparatively small tread-surface and a swelling lateral surface. To deal with such heels, it is necessary to provide pressure means which engage not only the tread-surface of the heel, but also the lateral surface, generally the side at the rear. Such a heel-engaging mechanism is disclosed in Patent No. 1,269,654, Standish, June 18, 1918, in which a member which engages the tread-surface and another member which is forked to engage the rear sloping surface of the heel, are so connected by gearing that they are balanced. This arrangement is preferably such that the tread member 30 contacts with the heel first, and retires under the relative approaching movement between the heel supported on the shoe and the head, or like part, which carries the heel-engaging members, thus causing the other member to contact with the heel. In this way, the heel is first measured by this automatic adjustment of the members to its particular dimension, and then clamped against the heel-seat-surface of the shoe. I have found 40 in practice that to accomplish the secure attachment to shoes of heels of the kind in question, particularly when made of wood, a degree of pressure is often required upon the rear surface of the heel which might, with some styles or grades, cause danger of breakage if applied to the tread-surface. It is accordingly an object of the present invention to provide means whereby such a heel

will be held securely, without risk of damage thereto.

A feature of the invention resides in the provision in a machine for operating upon heels of the type mentioned, of means adapted to engage the heel, both upon its tread-surface and its lateral surface, and to apply 60 an invariably greater final pressure to the lateral surface than to the tread.

A further feature of the invention consists in pressure means for a machine operating upon heels, such pressure means, comprising relatively movable members for contact with different portions of a heel, which members are interconnected and have means for fixing them against relative movement. More specifically, the connections between 70 the contact members may include a pinion having bearings, which are of larger diameter than the pitch diameter of the pinion, so that upon the members both engaging the heel, further relative movement of the 75 pressure means and shoe causes a locking action in the pinion-bearing, and the pressure applied by one of the members, preferably unyieldingly supported, is increased substantially as compared with that applied 80 by another which is yieldingly supported.

The above and other features of the invention will be fully evident from the following description of a preferred construction of the invention applied to a machine 85 of the type shown in the previously-mentioned patent.

In the accompanying drawing,

Figure 1 is a side elevation, partly in section, of as much of the machine as is 90 necessary to illustrate the invention;

Fig. 2 is an enlarged sectional view on the line 2—2 of Fig. 1; and

Fig. 3 shows in perspective the connecting pinion.

The shoe-supporting jack A and the opposed pressure-head B, the latter carrying the contact member 4 for engaging the tread-surface of a heel, and the contact member 5 arranged to bear upon its rear sloping surface, with the intermediate pinion 1 meshing with racks 2 and 3 upon the members 4 and 5, respectively, to cause them to move relatively to one another, may be generally 100 as shown and described in the patent already 105 mentioned. In order that greater pressure

may be obtained upon the rear surface of the heel than upon the tread when the measuring of said heel is completed, the pinion 1 is mounted in bearings of a size which 5 produce a considerable amount of friction when force is applied thereto through the medium of the racks. In the particular arrangement illustrated, the ratio of the diameters of the pitch circle of the pinion and 10 its bearing surfaces are as 3 to 5. The pinion preferably has at each end of its toothed portion, cylindrical bearing disks 6 and 7 fastened to it by keys 8, which disks furnish the journals of the pinion and are received in bearings formed in the usual carriage 10, which is adjustable upon the head B, and in a plate 11 fixed to the carriage. The pinion may be held in place in its bearings by the racks 2 and 3 engaging it on each 15 side between the disks, which, by their contact with the opposite sides of the racks, act to prevent lateral displacement of the pinion.

With this construction, it is found that a locking action occurs as soon as any measurable degree of pressure follows the contact of the rear member 5 with the heel. 20 Further relative approach of the heel-engaging members consequently directly increases the pressure between them; but in order that the heel may not be injured by the pressure of the member 4 upon the tread-surface, a yield is provided for said surface greater than any which may exist in the member 5, so that the result of the movement 25 between the shoe and the heel-engaging members after the contact of the member 5 is to increase the pressure of such member, without materially or to an injurious extent increasing the pressure upon the tread by the member 4. The yieldability of the member 4 is shown as furnished by a block 12 of rubber, or other resilient material, positioned between the members and a tread-surface-engaging plate 13, which may 30 be of metal. The plate 13 has formed upon it an upwardly-extending shank 14 arranged to slide within the member. This shank is prevented from turning in its mounting and is limited in its downward movement by a 35 conical pointed screw 15, which enters a groove 16 in the stem, and which engages an inclined face 17 at the end of the groove. The conical surface of the screw and the 40 inclined face of the groove by their contact 45 provide an adjustment by which the initial compression of the block 12 may be varied. The screw may be locked in its adjusted position by a nut 18.

As has been indicated, the above arrangement 45 allows of the retention of the feature of equal movement of the heel-engaging members during the measuring operation. However, the production of the difference 50 of pressures of the members upon the heel 55 may be obtained by other forms of connec-

tion, which will be apparent to those skilled in the art. It will be obvious also that heel-engaging means of the nature described may be applied to machines for performing other operations upon shoes than the attachment 70 of heels, for instance the breasting of heels, and it should be understood that the heel-engaging means may either itself apply the pressure by its movement toward the heel, or may act as an abutment to resist movement of the heel pressed against it; and references throughout this specification to pressure-applying or exerting means should be considered as applicable to either the function of actively applying pressure or of offering resistance to movement.

Having thus described my invention, what I claim as new and desire to secure by United States Letters Patent is:

1. In a machine for operating upon shoes, pressure means having portions relatively movable in the operation of the machine for contact with the tread and lateral surfaces of a heel and constructed and arranged to exert an invariably greater final pressure upon the lateral surface than upon the tread. 85
2. In a machine for operating upon shoes, pressure means having movable portions for contact with the tread and lateral surfaces of a heel, and means for locking the pressure-portions against movement, such pressure-portions being constructed and arranged to act more yieldingly upon the tread-surface than upon the lateral surface. 95
3. In a machine for operating upon shoes, pressure means having relatively movable members for contact with different portions of a heel, connections for moving one of said members from another, and means constructed and arranged to cause the application of different pressures by the members to different heel-portions. 105
4. In a machine for operating upon shoes, pressure means having relatively movable members for contact with the tread and lateral surfaces of a heel, connections for moving one of said members from another, and means constructed and arranged to cause the application of greater pressure 115 to the lateral surface than to the tread. 110
5. In a machine for operating upon shoes, pressure means having relatively movable members for contact with the tread and lateral surfaces of a heel, the pressure member for the tread-surface presenting thereto a yieldable contact-surface, and connections for moving one of said members from another. 120
6. In a machine for operating upon shoes, pressure means having relatively movable members for contact with the tread and lateral surfaces of a heel, and automatic means for fixing said members against such relative movement. 125

7. In a machine for operating upon shoes, one of said members from another, and means co-operating with the connections for locking said members against movement. 35
- 5 8. In a machine for operating upon shoes, pressure means having relatively movable members for contact with the tread and lateral surfaces of a heel, the tread contact member being yieldable, and means controlled by their contact for fixing said members against such relative movement. 40
- 10 9. In a machine for operating upon shoes, pressure means having relatively movable members for contact with the tread and lateral surfaces of a heel, and means made effective upon contact of the members with the heel for locking them against movement. 45
- 15 10. In a machine for operating upon shoes, pressure means having relatively movable members for contact with different portions of a heel, and means acting upon the contact of both members with the heel-positions 50 for fixing said members against such relative movement. 55
- 20 11. In a machine for operating upon shoes, pressure means having relatively movable members for contact with different portions of a heel, and means made effective by the contact of the members with the heel for fixing said members against such relative movement. 60
- 25 12. In a heel-attaching machine, a pressure-head, a plurality of heel-engaging members movable thereon, movement-transmitting connections between the members, and locking means associated with the connections. 40
- 30 13. In a heel-attaching machine, a pressure-head, a plurality of heel-engaging members movable thereon, movement-transmitting connections between the members, and frictional locking means associated with the connections. 45
- 35 14. In a heel-attaching machine, a pressure-head, a plurality of heel-engaging members movable thereon, gearing connecting the members, and bearings for an element of the gearing, said bearings being provided with locking surfaces arranged to prevent movement of the gearing when pressure is exerted by the members. 55
- 40 15. In a heel-attaching machine, a pressure-head, a plurality of heel-engaging members movable thereon, gearing connecting the members and including a pinion, and bearings for the pinion having a greater diameter than the pitch of the pinion. 60
